UNITED STATES PATENT OFFICE

KARL C. RANDALL, OF EDGEWOOD, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed November 27, 1929. Serial No. 410,113.

My invention relates to circuit breakers responsive portion of the trip mechanism may and particularly to enclosed oil-filled circuit breakers having automatic tripping means for causing such circuit breakers to open under predetermined current conditions.

Heretofore bushing or ring type current transformers could be practically used in conjunction with trip coils to control high-tension circuit breakers only where the current values exceed certain limits and were not practical for overload and short-circuit protection below circuit-breaker ratings of about fifty amperes. It was, therefore, necessary to employ other means for controlling high-tension circuit breakers of relatively low current ratings. For this purpose, wound-primary type transformers are usually employed, but these have the disadvantage of requiring relatively expensive insulations and occupy considerable space exterior of the circuit-breaker housing.

An object of my invention is to provide a control device for high-tension low-current circuit breakers wherein, a current transformer immersed in oil within the circuit-breaker housing is employed to energize a thermal element that is operative, on relatively low currents, for tripping the latch mechanism of the circuit breaker.

Another object of my invention is to provide a high-tension circuit breaker that shall be controlled by a relatively simple and inexpensive control device that affords a time delay for causing opening of the circuit breaker when an objectionable overload has endured for a predetermined time.

A further object of my invention is to provide a circuit breaker wherein the trip mechanism may be energized by a relatively small current supplied by a current transformer associated with one of the circuit-breaker contacts.

A further object of my invention is to provide a circuit breaker having the above-noted characteristics wherein the trip mechanism may be protected against destructive forces induced by sudden overload or short-circuit surges.

A further object of my invention is, to provide a circuit breaker wherein the current

be enclosed within the circuit-breaker housing and which is relatively compact and may be carried upon the bushing of the stationary contact or upon the moving contact.

55

A further object of my invention is to provide a circuit breaker having a thermal-responsive trip mechanism that will be influenced by current proportional to that flowing through the circuit-breaker contacts and which will not be responsive to changes in ambient temperature.

60

A further object of my invention is to provide a circuit breaker with a trip mechanism to be energized by a current transformer and wherein the usual expensive insulation may be dispensed with by placing the transformer in the circuit-breaker housing and immersing it in the usual insulating fluid within the housing.

65

These and other objects that will be made apparent throughout the further description of my invention are attained by means of the apparatus hereinafter described, and illustrated in the accompanying drawings, 75 wherein

Figure 1 is a vertical section through a circuit breaker embodying features of my invention,

70

Fig. 2 is a vertical section, on an enlarged scale, showing a detail of the current-responsive trip mechanism shown in Fig. 1.

Fig. 3 is a transverse section through the device shown in Fig. 2, taken on the line III—III thereof,

85

Fig. 4 is a vertical section through a circuit breaker disclosing a modified form of the thermal-responsive trip mechanism, and

Fig. 5 is a wiring diagram of a modified control circuit.

90

Referring to the drawings and particularly to Fig. 1, the circuit-breaker apparatus comprises a metal housing 8 containing insulating fluid 9, such as oil, and provided with a metal cover 11 that is fixed to the housing by means of bolts 12. The cover 11 supports a pair of contact bushings 13 which support stationary contacts 14 having exteriorly projecting terminals 15 to which the feed conductors 16 are connected.

95

100

The stationary contacts 14 are adapted to be connected by a movable bridging contact device 17 that is provided with an operating rod 18 by means of which the movable contact device 17 is raised to closed position.

8 The bridging contact device 17 comprises a pair of contact blades 19 mounted upon the ends of an insulating bar 20, the contacts being connected by a conductive cable 21 that is connected to the terminals 22 of the primary coil 23 of a wound-type transformer 24. The transformer 24 is mounted upon the insulating bar 20 and its purpose will hereinafter appear.

15 The nature of the contact between the stationary contact jaws 14 and the contact blades 19 of the bridging contact 17 is such that, when the rod 18 is released, the bridging contact 17 is caused to fall away from the contacts 14 under the influence of gravitational force.

18 The bridging contact device 17 is retained in closed position by means of a latch bar 25 that engages a notch 26 in the operating rod

25. A purpose of my invention is to provide a simple and inexpensive means for tripping the circuit breaker to open position, in response to an overload condition, after an overload has persisted in the circuit a predetermined time.

30 Heretofore, high-tension low-current circuit breakers have been opened by trip-coil devices energized by transformers mounted exteriorly of the circuit breaker and requiring relatively expensive insulation. In order to reduce the cost of the trip mechanism, a transformer 24 of a simple wound-primary type is mounted upon the movable circuit-breaker contact which is immersed in the oil 35 within the circuit-breaker tank or casing.

40 In order that the circuit breaker may be tripped to open position under predetermined current conditions, I have provided a trip rod 32, made of insulating material, which projects, exteriorly of the cover 11, through an opening 33 therein and is brought into operative relation to a toggle link constituting a part of the trip mechanism hereinafter described.

45 The latch 25 is slidably supported in a bracket 34 that is mounted upon the cover 11 and is actuated by a bell-crank lever 35 pivotally mounted on the bracket. The lever 35 is loosely connected to a vertical trip rod 36 slidably mounted in a guide 37, the rod being pivoted to the knee pivot 38 of a pair 50 of toggle links 39 and 41 that are movably mounted, by slot-and-pin connections 42, upon the bracket 34.

55 An over-center spring 43, that is connected to the free ends of the links 39 and 41, serves to bias the knee of the pivot toward either an upward position, as shown, or a downward position into engagement with the up-

per end of a resetting pin 44 that is pivoted to a toggle 45. The knee of the toggle 45 is pivoted to a link 46 that is pivotally connected to the operating shaft 18 of the circuit breaker.

70 When the release mechanism is in the latched position shown in Fig. 1, the knee pivot 38 of the toggle is slightly above the center of the pins of the slot-and-pin connection 42 of the toggle links. The trip rod 32 is of such length that, when the bridging contact member 17 is in closed position, the upper end thereof lies directly beneath the overhanging portion 40 of the toggle link 41, and a slight upward movement thereof will cause the knee pivot 38 of the toggle to move below the above-noted center line, at which time, the spring 43 will cause the toggle to collapse downwardly until the knee thereof rests upon the end of the resetting pin 44.

80 The enlarged end of the release rod engages the horizontal arm of the bell-crank lever 35 and causes withdrawal of the latch 25 and subsequent opening of the contact member 17 which falls away from the stationary contacts 19. As the shaft 18 drops, the link 46 causes the toggle 45 to move through its straight position and raise the resetting pin which resets the toggle. When the contact member 17 is moved to closed position, the spring 47, connected to the lever 35 causes the latch to be moved into the notch 26 and to thereby retain the shaft 18 in closed position.

100 With particular reference to Figs. 1, 2 and 3, it will be seen that the trip rod 32 is mounted upon a pair of flexible diaphragms 48 and 49 that are supported by a cylindrical casing 51 to serve to so seal the ends thereof that the liquid within the circuit breaker housing cannot enter within the casing 51, which is mounted upon the movable bridging contact member 17.

105 A bimetal element 52, of U-shape, and having a pair of terminals 53 and 54, is mounted in horizontal position within the casing 51, the terminals 53 and 54 extending through an insulating bushing 55 in the wall of the casing, as indicated in Figs. 2 and 3. The terminals are respectively connected to the terminals of a secondary winding 56 of the transformer 24. The current induced therein passes through the bimetal element 52 and is substantially proportional to that flowing through the winding 23 and the bridging contact device 17.

110 A second bimetal element 57 is mounted upon the casing 51 and interiorly thereof and directly opposite the bimetal element 52, as indicated in Figs. 2 and 3. The bimetal element 52 is so positioned that the free end thereof is deflected upwardly when heated to a predetermined temperature, while the bimetal element 57 is so positioned that a rise

in temperature of the space within the casing 37 causes the free end thereof to move downwardly. The bimetal elements are so proportioned with respect to one another that the free ends thereof are moved in opposite directions a substantially equal amount in response to a change in ambient temperature of the space within the casing 51.

The bimetal elements 52 and 57 are connected to the trip rod 32 by means of a yoke 58 pivotally mounted upon the trip rod and having downwardly extending fingers 59 and 61 that respectively engage the bimetal elements 52 and 57. Since the rod 32 is connected to the diaphragms 48 and 49, which have substantially equal external pressure thereon, the rod 32 is free to move in response to movement of the bimetal elements 52 and 57.

Since, ordinarily, the free end of the bimetal element 52 moves upwardly the same distance as the free end of the bimetal element 57 moves downwardly in response to a rise in ambient temperature, substantially no movement of the rod 32 will result from variations in the ambient temperature of the control mechanism. However, should an abnormal current flow through the circuit breaker and the bridging contact device 17, a correspondingly increased current will flow through the bimetal element 52 which is connected to the secondary transformer winding 56.

At such time, the free end of the bimetal element 52 will move upwardly, while the free end of the bimetal element 57 remains practically stationary, causing a sufficient upward movement of the rod 32 to trip the toggle and thereby release the operating shaft 18 to permit the circuit-breaker contact device 17 to fall to open position.

The bimetal element 52, preferably, may have inverse time characteristics and may be calibrated to cause the circuit breaker to open when an overload of predetermined proportions has endured for a predetermined time.

It will be noted that the current-responsive device is relatively simple in construction and, because of its compact proportions may be carried conveniently upon the bridging contact and immersed in the fluid within the circuit-breaker tank. The control device, being thus enclosed, is protected from contact with extraneous objects without requiring special coverings, and tampering therewith is precluded.

Current transformers for high-tension service, such as are usually employed with high-tension low-current circuit breakers, are placed in separate tanks and require special, relatively expensive insulation and are relatively large. By immersing the transformer in the insulating fluid within the circuit-breaker housing, the transformer parts may be reduced in size, and no special in-

sulation is required. Consequently, the size and cost of the transformer may be materially reduced.

Referring to Fig. 4, a modified form of control mechanism for a circuit breaker similar to that shown in Fig. 1, is illustrated. The trip mechanism, which is entirely immersed in the insulating fluid within the tank, is similar to that shown in Fig. 1, but the transformer and thermal device are mounted upon one of the insulating terminal bushings.

The advantage of this construction resides in the removal of all control mechanism from the bridging contact device, thereby reducing the weight and the inertia of the movable contacts and permitting of high-speed operation. Furthermore, all of the tripping mechanism is enclosed within the tank and immersed in the insulating fluid, thereby affording complete protection to such mechanism.

The current transformer 24 for energizing the bimetal element 52 is mounted upon the insulating bushing 13 by means of a clamp 63, and the inner end of the terminal 15 is provided with an insulating bushing 64 in which the stationary contact 14 is threaded, in such manner that it is insulated from the terminal 15.

The thermal device 51 is mounted upon a bracket 65 that is secured to the bushing 64 is, accordingly, insulated from the housing and the terminals thereof. The terminals of the primary winding 23 of the current transformer are connected to the inner end of the terminal 15 and the contact 14, respectively, in such manner that all of the current passing through the circuit breaker passes through the primary winding. The operation of the circuit breaker is substantially the same as that of the breaker shown in Fig. 1.

In Fig. 5, I have shown a means for protecting the bimetal element against abnormal current surges that would be injurious to it, which comprises a reactor 66 for shunting the bimetal element. Under normal operating conditions, the current is so divided that it flows mainly through the bimetal element but, when a heavy surge is induced in the secondary winding 56 of the transformer, the core of the reactor becomes saturated and permits the main portion of the current to pass through the coil 67 of the reactor and thus divert destructive currents from the bimetal element.

While I have illustrated several embodiments of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. The combination with an enclosed circuit breaker having a casing, a movable con-

tant member within the case and a means carried by the casing for releasably retaining the said member in closed position, of a current-responsive means for actuating the releasing means in response to predetermined current conditions, carried by the movable contact member, and so movable thereby, that it is placed in operative relation to the said releasing means when the contact member is in closed position.

2. The combination with a circuit breaker having a movable contact member and a means for releasably retaining said member in closed position, of a current-responsive member carried upon said member and operated by current induced by that passing through the contact member for actuating the retaining means.

3. The combination with a circuit breaker having a pair of relatively movable contact members and a means for releasably retaining the contact members in engaged position, of a current-responsive member carried upon one of said contact members and operated by current induced by that passing through one of the contact members for actuating the releasing means.

4. The combination with an enclosed circuit breaker having a movable contact member immersed in liquid and a means for releasably retaining said contact member in closed position, of an enclosed current-responsive device mounted upon the immersed contact member and energized by current passing through the contact member for actuating the retaining means.

5. The combination with an enclosed circuit breaker having a movable contact member and a releasing member mounted upon the enclosure for releasably retaining the contact member in closed position, of a current-responsive member carried upon the movable contact member and movable therewith into operative relation to the releasing member when the contact member is moved to closed position.

6. A circuit breaker comprising a housing having a cover, a contact fixed to the cover, a movable contact within the housing for engaging the first contact, means mounted on the cover for releasably retaining the movable contact in closed position, and a current-responsive means for actuating the releasing means and carried upon the movable contact and operatively associated with the releasing means only when the movable contact is in closed position.

7. A circuit breaker comprising a tank containing insulating fluid, a pair of relatively movable contact members within the tank and immersed in the insulating fluid, means for releasably retaining the contact members in closed position, a current-responsive element for releasing the retaining means, and

a transformer within the tank and immersed in the insulating fluid for energizing the said current-responsive means.

8. A circuit breaker comprising a tank containing insulating fluid, a pair of relatively movable contact members within the tank and immersed in the insulating fluid, means for releasably retaining the contact members in closed position, a current-responsive element immersed in the insulating fluid for releasing the retaining means, and a transformer within the tank for energizing the current-responsive means.

9. A circuit breaker comprising a tank containing insulating fluid, a pair of relatively movable contact members within the tank and immersed in the insulating fluid, means for releasably retaining the contact members in closed position, a current-responsive element immersed in the insulating fluid for releasing the retaining means, and a transformer within the tank connected in the circuit containing the contact members for energizing the current-responsive means.

10. A circuit breaker comprising a tank containing insulating fluid, a pair of relatively movable contact members within the tank and immersed in the insulating fluid, means immersed in the insulating fluid for releasably retaining the contact members in closed position, a current-responsive element for releasing the retaining means, and a transformer within the tank for energizing the said current-responsive means.

In testimony whereof, I have hereunto subscribed my name this 21st day of November, 1929.

KARL C. RANDALL.
